Attorney

UNITED STATES PATENT OFFICE.

WILLIAM G. WOOD, OF SACRAMENTO, CALIFORNIA.

DRAG-BUCKET.

1,197,991.

Specification of Letters Patent. Patented Sept. 12, 1916.

Application filed April 24, 1916. Serial No. 93,156.

To all whom it may concern:

Be it known that I, WILLIAM G. Wood, a citizen of the United States, residing at Sacramento, in the county of Sacramento and State of California, have invented new and useful Improvements in Drag-Buckets, of which the following is a specification.

The present invention relates to improvements in drag buckets used in excavating machines. Great difficulty is often experienced in dropping out of the bucket the load contained therein, especially if it is of clayey or sticky material.

The object of the present invention is to provide a means whereby, when the bucket is tilted for the purpose of dumping its load, the load may be positively discharged from the bucket.

In the accompanying drawing, Figure 1 is a broken side view of a drag bucket constructed in accordance with my invention, in the position in which it is being dragged along the surface of the ground; Fig. 2 is a similar view of the bucket in the position in which it is tilted for the purpose of dumping; Fig. 3 is a cross sectional view of the bucket.

Referring to the drawing, 1 indicates a drag bucket having the usual teeth 2, drag chains 3 and bail 4 by which the drag bucket can be suspended. To the inner square ends of the pivot bolts 6 of the bail 4 are secured, so as to turn therewith, crank arms 7, to the outer ends of which are pivotally secured ends of links 8, the other ends of which are pivotally secured, as shown at 9, to side plates 11 located closely adjacent to the sides 12 of the body of the bucket, said side plates 11 being riveted, as shown at 13, to a movable back 14 located to normally rest against the back 15 of the bucket, between which back and the side plates 11 are riveted longitudinal slide bars 16, between which slide bars and the bottom 17 of the bucket are secured slidable cross bars 18, the ends of which slide between the sides 12 and guides 19, riveted upon said sides. The cross bars and the front edge of the curved movable back are formed with beveled edges 24, which shear off from the bottom 17 of the bucket any material that may be adhering thereto. To said longitudinal bars 16 are secured lower ends of oblique brace bars 20, the upper ends of which are secured to the movable back 14. The result of this construction is that, when the bucket is being

dragged forward by the pull chains, the false or movable back 14 is in its rearmost position next the back 15 of the bucket. But, when the bucket is suspended from the bail, so that it extends in an approximately vertical direction, as shown in Fig. 2, then, by reason of the movement of the crank arms 7 with relation to the bucket, the movable back 14, longitudinal and transverse slide bars 16, 18, and oblique braces 20 move forward in the bucket, thereby shearing off any material that might be adhering to the bottom of the bucket, so that the load readily drops therefrom.

I claim:

1. In combination with a drag bucket, means for moving the same in a longitudinal direction, and means for suspending the same vertically, bars movable in close proximity to the bottom of the bucket, and an operative connection between said bars and one of the aforesaid means, whereby said bars are so moved when the bucket moves relatively to said aforesaid means.

2. In combination with a drag bucket, means for moving the same in a longitudinal direction, and means for suspending the same vertically, longitudinal and transverse bars movable in close proximity to the bottom of the bucket, and an operative connection between said bars and one of the aforesaid means, whereby said bars are so moved when the bucket moves relatively to said aforesaid means.

3. In combination with a drag bucket, means for moving the same in a longitudinal direction, and means for suspending the same vertically, a back, longitudinal and transverse bars movable in close proximity to the bottom of the bucket, and an operative connection between said bars and one of the aforesaid means, whereby said bars and back are so moved when the bucket moves relatively to said aforesaid means.

4. In combination with a drag bucket, means for moving the same in a longitudinal direction, and means for suspending the same vertically, longitudinal bars movable longitudinally in close proximity to the bottom of the bucket, transverse bars secured to said longitudinal bars, guides on the sides of the bucket for said bars, a back connected to said longitudinal bars, braces connecting said back and longitudinal bars, and an operative connection between said bars and one of the aforesaid means, where-

2 by said bars are so moved when the bucket moves relatively to said aforesaid means.

5. In a drag bucket, a bail upon which said bucket is suspended, pivot bolts connecting said bucket to said bail, crank arms connected to said pivots, links connected to said crank arms, a movable back connected to said links, longitudinal slide bars connected to said back, and transverse bars con-

nected to said longitudinal bars and guides 10 for said transverse bars connected to the sides of the bucket, and an operative connection between said bars and one of the aforesaid means, whereby said bars and back are so moved when the bucket moves 15 relatively to said aforesaid means.

WILLIAM G. WOOD.
